W. W. CASSIDY

CANDY JUMPING JACK

Filed Aug. 2, 1926

UNITED STATES PATENT OFFICE.

WILLIS W. CASSIDY, OF SALT LAKE CITY, UTAH, ASSIGNOR TO SWEET CANDY COMPANY, OF SALT LAKE CITY, UTAH, A CORPORATION OF UTAH.

CANDY JUMPING JACK.

Application filed August 2, 1926. Serial No. 126,710.

My invention is a candy jumping jack which consists in the combinations, constructions and arrangements herein described and claimed.

5 The object of the invention is to provide a package of an edible commodity which also is a toy that can be manipulated to provide entertainment and amusement for children.

A more specific object of the invention is 10 to combine a plurality of wrapper-covered pieces of candy with a carton for holding pieces of candy so as to produce a toy, which in appearance and in operation, meets all the essential requirements for a jumping 15 jack and which at the same time keeps the pieces of candy well covered and protected until they have been removed from their covering members.

A still further object of the invention is 20 the provision of a candy jumping jack of the character described which is of convenient size to be readily vended, at a relatively low price and which is adapted to endure relatively hard usage without impairment or 25 soiling of the candy contents thereof.

A still further object of the invention is 30 the provision of a novel arrangement of paper-wrapped pieces of candy with a carton which contains other pieces of candy so that the said paper wrapped pieces of candy will 35 be jointedly connected with the carton and will constitute arms, legs and a head for the carton.

A still further object of the invention is 40 the provision in a candy jumping jack of a paper carton body and paper covered candy legs, arms and a head attached to the body, both the carton and the covering members the arms and legs and head of the device being adapted to be colored as desired and to have any suitable indicia, ornamentation or other matter produced thereon so as to add to the attractiveness of the device or to serve any other purpose.

45 Other objects and advantages of the invention will be apparent from the following description, considered in conjunction with the accompanying drawings, in which

Figure 1 is a perspective view of a candy jumping jack embodying the invention, 50

Figure 2 is a vertical section throughout the body of the device, showing the head and one of the legs of the device in elevation,

Figure 3 is a relatively enlarged fragmentary vertical section through the upper portion of the body of the device in a plane at right angles of Figure 2, showing the head and portions of the arms of the device in elevation, and

Figure 4 is a plan of a blank of which the 60 carton body of the device can be formed.

The carton body 1 of the device may be formed of a blank as shown in Figure 4 which comprises the substantially identical main rectangular portions 2 and 3, the relatively narrow substantially rectangular strip 4 between the members 2 and 3, the relatively narrow end strips 5 and 6 at the outer edges of the members 3 and 2, respectively, the top flap 7 at the upper end of the 70 member 3 and the bottom flap 8 at the lower end of the member 3. The upper and lower edges of the flaps 7 and 8, respectively, are convexly curved as shown. The member or portion 3 of the blank constitutes the back 75 of the carton, the member 2, the front, the members 6—5 one side wall, and the member 4 the other side wall of the carton when the blank has been folded along the vertical fold lines shown at 9, 10, 11 and 14 respectively 80 in Figure 4 until the member 2 is parallel with the member 3 and the member 6 has been folded onto the member 5 and secured to the latter by paste or any other suitable known means so that the lapped members 85 5—6 will be parallel with the member 4.

A number of paper wrapped sticks 13 of relatively hard candy or other suitable pieces of edible commodities or articles may now be placed within the carton body to 90 stiffen the carton body and to increase the weight of the body desirably as well as to contain and house such articles so that they can be vended. The articles 13 are retained in place in the carton body when the bottom flap 8 has been swung upwardly and bent

along the horizontal fold lines 14 and 15 respectively to partially overlap the front member 2 of the carton as shown in Figures 1 and 2. Suitable known means, such as 5 paste, may be employed to secure the flap 8 to the front member 2 of the carton in the position shown in Figures 1 and 2. The lower ends of the members 5, 4 and 6 of the aforesaid blank have similar convexly 10 curved notches as indicated at 5^a, 4^a and 6^a so that lateral openings will be produced in the lower ends of the side members of the carton body when the flap 8 has been 15 swung upwardly onto the front member of the carton body as shown in Figure 1. The 20 legs of the device comprise two similar paper wrapped sticks 17 of the relatively hard candy and the twisted upper ends 18 of the wrapper of the sticks 17 are arranged to 25 extend through the lateral openings at the lower ends of the side members of the carton body and are secured to each other within the lower end portion of the carton body by means of a clip 19 or other suitable fastening device. The members 17 thus will be 30 jointedly connected with the lower end portion of the carton and will dangle from the carton body in the manner of the legs of a jumping jack. The lower end portions of 35 the wrappers of the members 17 are twisted as indicated at 20 to cooperate with the twisted upper end portions of said wrappers to prevent accidental displacement of the wrappers from position to entirely cover and thus protect the candy contents of the 40 said wrappers. It will be understood of course that the upper end portions 18 of the wrappers of the articles 17 are secured to each other within the lower end portion of the carton before the flap 8 is secured to the 45 front member of the carton.

The upper flap 7 may be bent from the position shown in Figure 4 along the horizontal fold lines 21 and 22, respectively, to 50 position to overlap the front member 2 of the carton as shown in Figures 1 and 2. The flap 7 has an opening 23 formed therein intermediate the side edges of the flap and between the fold lines 12, 21 and 22. 55 A slit 24 extends from the edge of the flap 7 to the opening 23 for a purpose to be presently described. The members 5, 4 and 6 of the aforesaid blank have concavely curved upper edges indicated at 5^b, 4^b, and 6^b respectively so that lateral openings will 60 be provided at the upper ends of the side members of the carton body when the flap 7 has been folded downwardly to position to partially overlap the front member 2 of the carton and has been secured to the latter by paste or any other suitable known means. Before the flap 7 is secured to the front member 2 of the carton, the twisted lower end portion 25 of the wrapper 26 65 for a piece of relatively hard candy 27 is

secured by a clip 28 or like fastening device to a relatively stiff strip 29 of paste-board or other suitable material and then is moved through the slit 24 into the opening 23 so that the strip 29 will be disposed within 70 the upper part of the body of the carton transversely of the latter as shown to advantage in Figures 2 and 3. The twisted upper end portions 30 of the paper wrapper covered sticks of candy 31 then are arranged to extend through the lateral openings at the upper ends of the carton body into the space within the carton body underneath the flap 7. These upper end portions 30 of the wrappers of the members 31 are 75 secured together in the upper part of the carton body by a clip 32 or other suitable fastening device and thus will be flexibly connected with the upper part of the carton when the flap 7 has been secured in place 80 on the upper portion of the front member 2 of the carton as shown in Figure 1. The members 31 will dangle from the upper end portion of the carton body at opposite sides of the latter in the manner of arms of a jumping jack and the lower end portions of the wrappers of the members 31 are twisted as indicated at 33 to prevent accidental displacement of the wrappers from position to 85 completely cover the members 31. 90

The wrapper 26 for the aforesaid candy member 27 has its upper end portion twisted directly above the candy member 27 and secured at that place in twisted portion by a clip 34 while the extreme upper end portion 26 preferably is arranged substantially in a flaring or fan-shaped formation as indicated at 35. The lower end portion of the wrapper 26 is twisted and confined by a clip 36 so that the contents of the wrapper 26 will be completely covered. The candy member 27 is formed to cooperate with the wrapper 26 to constitute the head of the jumping jack and it will be obvious that the candy member 27 may be substantially oval along a plane that extends vertically through the body transversely of the body of the device. 100 105 110

The front and the rear sides of the member 26 may be substantially parallel and flat and the portion of the wrapper 26 that covers the front face of the member 27 may have suitable markings produced thereon to simulate the features of a toy man. An elastic string 37 may be attached at one end to the twisted portion of the wrapper 26 above the candy member 27. The upper end portion of the wrapper 27 may have suitable markings and lines produced thereon as indicated at 38 to represent the hair on the 115 head of the jumping jack. 120 125

The carton may be printed or otherwise finished in any suitable color or colors and may have markings produced thereon to simulate clothing. The wrappers of the 130

members 31 and 17 also may be colored or otherwise marked as desired.

From the foregoing description of the various parts of the device, the operation thereof may be readily understood. The device is both a container for candy and a toy which can be manipulated by children in the manner of the ordinary jumping jack so as to provide entertainment and amusement for the children without making the candy members of the device less clean and edible. When desired, the candy contents or members of the device may be removed from the covering members of the device and eaten. It thus will be manifest that the invention provides both a source of entertainment for children and a means for dispensing, in package form, a quantity of an edible commodity, such as candy, without any considerable increase in the selling price thereof.

Obviously, the invention is susceptible of embodiment in forms other than that illustrated in the accompanying drawings, and I therefore consider as my own, all such modifications and adaptations of the form of the device disclosed herein which fairly fall within the scope of the appended claims.

I claim:

1. As a new article of manufacture, a paper carton having opposite lateral openings adjacent to its upper and lower ends and having a vertical opening in its upper end, said carton being adapted to hold a plurality of sticks of candy or like articles and forming the body of a toy figure, a pair of paper wrapped sticks of candy forming arms and having the inner end portions of their wrappers extending into the upper part of said carton through the upper pair of lateral openings, the adjacent end portions of said wrappers being secured together within the carton a second pair of paper wrapped sticks of candy forming legs and having the upper end portions of their wrappers extending into the lower portion of said carton through the lower lateral openings of the carton and secured to each other, and a piece of relatively hard candy substantially oval in cross sectional configuration in one vertical plane forming a head and having a paper wrapper formed with a lower end portion extending into the upper part of said carton through said vertical opening in the upper end of the carton and retained in place therein.

2. As a new article of manufacture, a paper carton having opposite lateral openings adjacent to its upper and lower ends and having a vertical opening in its upper end, said carton being adapted to hold a plurality of sticks of candy or like articles and forming the body of a toy figure, a pair of paper wrapped sticks of candy forming arms and having the inner end portions of

their wrappers extending into the upper part of said carton through the upper pair of lateral openings, the adjacent end portions of said wrappers being secured together within the carton, a second pair of paper wrapped sticks of candy forming legs and having the upper end portions of their wrappers extending into the lower portion of said carton through the lower lateral openings of the carton and secured to each other, and a piece of relatively hard candy substantially oval in cross sectional configuration in one vertical plane forming a head and having a paper wrapper formed with its lower end portion extending into the upper part of said carton through said vertical opening in the upper end of the carton, a retaining strip attached to the lower end of the carton, the upper end member of said carton having a slit extending from one edge thereof to said vertical opening and through which the lower end portion of said last named wrapper may be moved into said vertical opening.

3. As a new article of manufacture, a paper carton having opposite lateral openings adjacent to its upper and lower ends and having a vertical opening in its upper end, said carton being adapted to hold a plurality of sticks of candy or like articles and forming the body of a toy figure, a pair of paper wrapped sticks of candy forming arms and having the inner end portions of their wrappers extending into the upper part of said carton through the upper pair of lateral openings, the adjacent end portions of said wrappers being secured together within the carton, a second pair of paper wrapped sticks of candy forming legs and having the upper end portions of their wrappers extending into the lower portion of said carton through the lower lateral openings of the carton and secured to each other, and a piece of relatively hard candy substantially oval in cross sectional configuration in one vertical plane forming a head and having a paper wrapper formed with a lower end portion extending into the upper part of said carton through said vertical opening in the upper end of the carton and retained in place therein, the end portions of said wrappers being twisted.

4. A toy including a carton forming the body of a figure and having a head, wrapped candy members forming the arms of such figure and having a flexible connection extending through one end portion of the body, and wrapped candy members forming the legs of such figure and having a flexible connection extending through the other end portion of the body.

5. A candy toy including a carton forming a body portion, a head in connection with one end of said body, wrapped candy members forming arms and legs at opposite

sides of the body, and flexible members separately connecting said arms and legs and extending through relatively opposite ends of the body.

5 6. A jumping jack including a body having a head and comprising a carton for holding pieces of candy, and a plurality of paper wrapped candy members respectively con-

stituting arms and legs, flexible connections between the arm members and between the leg members, and an elastic suspension element attached to said head member of the jumping jack, said body having means at the ends thereof to receive said flexible connections therethrough.

WILLIS W. CASSIDY.
